UNITED STATES PATENT OFFICE.

PHILIP A. BECKER, OF NEW YORK, N. Y.

ADJUSTABLE DISPLAY-LID.

1,094,193.

Specification of Letters Patent. Patented Apr. 21, 1914.

Application filed September 3, 1913. Serial No. 787,916.

To all whom it may concern:

Be it known that I, PHILIP A. BECKER, a citizen of the United States, and a resident of New York, borough of Brooklyn, 5 county of Kings, and State of New York, have invented a certain new and useful Improvement in Adjustable Display-Lids, of which the following is a full, clear, and exact specification.

10 This invention relates to a class of lids designed to be employed upon cigar boxes, or the like.

It is well known in the tobacco trade that the cigars of practically all brands vary in 15 lengths and diameters, and to properly accommodate the products the boxes, or containers therefor are made in a large number of distinct sizes, instead of being made according to a standard scale. Moreover, 20 when the cigars are displayed for sale the lids of the boxes are usually removed therefrom, or swung to an open position, thereby subjecting the products to exposure of the air, or the collection of dust, or the like 25 which invariably impairs the fragrancy thereof.

The present invention has for its object 30 primarily to overcome these objections by providing a display lid adapted to be adjusted to accurately fit boxes of various widths and lengths, whereby the lid may be manufactured in one, or a limited number of sizes so that it may be used upon the boxes of various brands of cigars, and which 35 is adapted to be detachably applied to the box in a manner for preventing the products from being exposed to the air, or collecting dust while on display as well as permitting the cigars to be conveniently dis- 40 pensed from the container.

Another object of the invention is to provide an adjustable display lid which permits interchangeable signs to be employed in conjunction therewith; and a further object 45 of the invention is to provide a form of extensible frame so that transparent plates of different dimensions may be removably mounted therein.

A practical embodiment of the invention 50 is represented in the accompanying drawing forming a part of this specification in which similar characters of reference indicate corresponding parts in all the views, the said invention being more fully de- 55 scribed hereinafter, and then pointed out in the appended claims.

In the drawings, Figure 1 is a perspective view of a box with one form of display lid embodying my invention applied thereto. Fig. 2 is a reverse view of the adjustable sign and the clamps employed in the display lid. Fig. 3 is a front view of the sign plate used in the lid. Fig. 4 is a fragmentary view, showing in detail, one end of the adjustable sign and one of the clamps of 60 the display lid. Fig. 5 is an enlarged section, taken on the line II—II of Fig. 1, and Fig. 6 is an enlarged section of a slightly modified form of the extensible frame shown in Fig. 5. 70

The adjustable display lid has a plate of 75 glass, or other transparent material, as 10, which is substantially rectangular in shape so as to be movably applied upon the open top of the body of preferably a cigar box, 11, having a lid hinged to its rear wall, not shown, and said body of the box being of a well-known construction having side walls 13 and 14, and a front wall 15 which is of less height than the side walls, whereby a space 16 is provided above the top edge 80 of the front wall and between the upper edges of the side walls of the box.

The transparent plate 10 is cut preferably of a size to rest upon the upper edges 85 of the side walls of the box when closed thereupon, and serving to permit the space 16 of the box to be closed when the transparent plate is resting on the side walls thereof, upon the front longitudinal edge of 90 the transparent plate is an extensible protecting element, or frame 17 which also serves to prevent the transparent plate from being accidentally damaged, or broken when in use. The protecting element, or 95 frame 17 has two interfitting members 18 and 19, one of which is smaller than the other so as to be extensibly movable with relation to each other and both of said members may be made of spring metal in tubular form having a flat, or slightly curved top plate 20 and an integral approximately V-shaped depending part in cross-section, as 21, which has its free edge spaced from the top plate to provide a slot 22 longitudinally thereof so that by the exertion of slight force the top plate and the depending flange of each member may be guided apart for permitting the front edge of the transparent plate to be inserted and tightly held 105 therebetween. While the protecting element, or frame 17 is preferably formed of two 110

extensible members, in order to be readily fitted upon transparent plates of various lengths, it will be understood that the frame may consist of only one member which may be employed with equal efficiency as occasion requires.

For the purpose of permitting transparent plates of various dimensions to be detachably applied to the lids of boxes of different sizes, I provide two clamps, as 23 and 24, both of which are alike in formation. Each of the clamps 23 and 24 has two holding members, or sleeves 25 and 26 which are integrally formed upon the ends of a plate 26^a which is curved so that the sleeves are disposed at an angle with relation to each other. The sleeves 25 and 26 of each of the clamps may be alike in formation, each being formed with parallel spaced side plates 27 and 28 and a bridging plate 29 on one edge thereof, whereby each sleeve is approximately U-shaped. In mounting the clamps upon the transparent plate 10 the sleeves 25 thereof are mounted on the opposite side edges of the transparent plate at its corresponding corners which are opposite to the frame 17, as shown in Fig. 1, and to hold the sleeves against accidental displacement to said transparent plate through the top plate 28 of each sleeve is a threaded opening in which is directed a thumb screw 30 which when accordingly rotated will tightly engage the transparent plate. To detachably connect the transparent plate 10 to the lid 35 of a box the sleeves 26 of the clamps are guided over the side edges of the box lid, and these sleeves may be tightly held to the lid by likewise providing through the plate 28 of each of said sleeves 26 a threaded opening in which is directed a thumb screw 31 adapted to be rotated into engagement with the box lid. By detachably connecting the clamps 23 and 24 in this manner to the box lid the transparent plate may be swung to open, or closed positions upon the open top 40 of the body of the box by moving the lid of the box backwardly, or forwardly relatively to the body of the box.

In conjunction with this form of display lid I may employ an extensible sign, as 32, adapted to be used upon boxes of various lengths, and which is of a form whereby the names of different brands of cigars, or different prices may be interchangeably used when the goods are displayed for sale. The sign 32 consists of two plates 33, 34, and a slide, as 35. The plates 33 and 34 are similarly formed, each having its corresponding lower and upper edges bent over to provide flanges 36 and 37, and both of said flanges are spaced from the plate to form longitudinal grooves, as 38 and 39, Fig. 4. The opposite ends of the flanged faces of the plates 33 and 34 are soldered, or otherwise fastened to the clamps

23 and 24 in a manner so that the plates will be disposed on alignment transversely of the box lid and so that the free ends thereof are in opposed relation. On the faces of the plates 33 and 34 which are thereby opposed to the transparent plate 10 may be painted, or otherwise inscribed one or more suitable names, as indicated at 40. The slide 35 is preferably in the form of an elongated plate of a width to adapt it to be freely movable in the grooves 38 and 39 of the plates 33 and 34, and on one face of said slide may be painted one, or a number of prices, or other characters, as 41. The slide 35 is arranged in the grooves of the plates 33 and 34 so that one, or more of the characters 41 may be exposed to view when the display lid is applied upon a box, and any desired number of said slides may be provided whereby interchangeable signs may be used with the device as occasion requires.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope of the appended claims.

Having thus described my invention, I claim as new and desire to secure by Letters Patent:—

1. A display lid of the character described, comprising a transparent plate adapted to be movably applied upon the open top of a box having a space above the upper edge of its front wall and said box also having a lid hinged thereto, a removable frame provided upon the front edge of the transparent plate so as to be movably disposed in the space above the front wall when the plate is closed upon the box, and two clamps detachably fastened to the rear part of the plate and detachably held to the lid of the box, whereby the transparent plate may be swung to open or closed positions upon the body of the box when its lid is accordingly moved.

2. A display lid of the character described, comprising a transparent plate adapted to be movably applied upon the open top of a box having a space above the upper edge of its front wall, and said box also having a lid hinged thereto, a frame of yielding material removably held upon the front edge of the transparent plate so as to be movably disposed in the space above the front wall when the plate is closed upon the box, two clamps detachably fastened to the rear part of the plate and detachably held to the lid of the box, whereby the transparent plate may be swung to open or closed positions upon the body of the box when its lid is accordingly moved, and means provided upon

- the clamps for permitting interchangeable signs to be removably mounted upon the transparent plate.
3. A display lid of the character described, comprising a transparent plate adapted to be movably applied upon the open top of a box having a space above the upper edge of its front wall and said box also having a lid hinged thereto, an extensible frame removably held upon the front edge of the transparent plate so as to be movably disposed in the space above the front wall when the plate is closed upon the box, and two clamps detachably fastened to the rear part of the plate and detachably held to the lid of the box, whereby the transparent plate may be swung to open or closed positions upon the body of the box when its lid is accordingly moved.
4. A display lid of the character described, comprising a transparent plate adapted to be movably applied upon the open top of a box having a space above the upper edge of its front wall, and said box also having a lid hinged thereto, an extensible frame removably held upon the front edge of the transparent plate so as to be movably disposed in the space above the front wall when the plate is closed upon the box, two clamps detachably fastened to the rear part of the plate and detachably held to the lid of the box, whereby the transparent plate may be swung to open or closed positions upon the body of the box when its lid is accordingly moved, and means provided upon each of the clamps, said means being adapted for coöperative use to permit interchangeable signs to be removably mounted upon the transparent plate.
5. A display lid of the character described, comprising a transparent plate adapted to be movably applied upon the open top of a box having a lid hinged thereto, and two clamps, each having two integral sleeves disposed at an angle relatively to each other, one of the sleeves of each clamp being removably held to the transparent plate at one edge thereof, and the second sleeve of each clamp being adapted to be removably applied to the box lid, whereby the transparent plate may be swung to open or closed positions upon the body of the box when its lid is accordingly moved, two plates each having one of its ends secured to one of the sleeves of each clamp, said plates being disposed on alinement toward each other, and each of said plates having two parallel spaced grooves longitudinally thereof, whereby interchangeable signs may be adjustably inserted in the grooves.
6. A display lid of the character described, comprising a transparent plate adapted to be movably applied upon the open top of a box having a lid hinged thereto, two clamps, each having two integral sleeves disposed at an angle relatively to each other, one of the sleeves of each clamp being removably held to the transparent plate at one edge thereof, and the second sleeve of each clamp being adapted to be removably applied to the box lid, whereby the transparent plate may be swung to open or closed positions upon the body of the box when its lid is accordingly moved.
7. A display lid of the character described, comprising a transparent plate adapted to be movably applied upon the open top of a box having a lid hinged thereto, and two clamps, each having two integral sleeves disposed at an angle relatively to each other, one of the sleeves of each clamp being disposed over an edge of the transparent plate, means provided upon each sleeve for removably holding the sleeve to the transparent plate, and the second sleeve of each clamp being disposed upon one of the edges of the lid of the box, and means provided upon each of the second sleeves for removably holding the sleeve to the box lid, whereby the transparent plate may be swung to open or closed positions upon the body of the box when the lid is accordingly moved.
8. A display lid of the character described, comprising a transparent plate adapted to be movably applied upon the open top of a box having a lid hinged thereto, two clamps, each having two sleeves disposed at an angle relatively to each other, one of the sleeves of each clamp being removably held to the transparent plate at one edge thereof, and the second sleeve of each clamp being adapted to be removably applied to the box lid, whereby the transparent plate may be swung to open or closed positions upon the body of the box when its lid is accordingly moved, two plates each having one of its ends secured to one of the sleeves of each clamp, said plates being disposed on alinement toward each other, and each of said plates having two parallel spaced grooves longitudinally thereof, whereby interchangeable signs may be adjustably inserted in the grooves.

This specification signed and witnessed this second day of September, A. D. 1913. 115
